UNITED STATES PATENT OFFICE.

MAURICE PHILIPPE FAVRE-BULLE, OF PARIS, FRANCE.

ELECTROMAGNETIC CLOCK.

1,411,243.

Specification of Letters Patent. Patented Mar. 28, 1922.

Application filed September 23, 1920. Serial No. 412,338.

To all whom it may concern:

Be it known that I, MAURICE PHILIPPE FAVRE-BULLE, a citizen of the Republic of France, residing at Paris, Department of the Seine, France, have invented new and useful Improvements in Electromagnetic Clocks, of which the following is a specification.

The present invention relates to improvements in electro-magnetic clockwork mechanism applicable to all clocks of the known type in which the pendulum is moved by electro-magnetic means and actuates and controls the movement of the hands.

As is known, in clocks of the type under consideration the oscillations of the pendulum are kept up by the action of an intermittent current, passing through a coil, upon a system of magnets, the magnets being fixed 20 to the pendulum and the coil being stationary, or vice versa.

The clockwork mechanism according to the present invention permits of ensuring the transmission of the movement of the pendulum to the hands under the most favorable conditions and also of causing the periodic closure, at the proper time, of the electric circuit feeding the coil which produces the electro-magnetic force which keeps 30 up the oscillations of the pendulum.

It is characterized by special features which ensure perfect electrical and mechanical operation by means of parts which are of very simple and strong design and at 35 the same time are extremely cheap to manufacture.

According to the invention, this mechanism comprises an actuating pendulum, the oscillation of which is kept up by intermittent electro-magnetic action and the movement of the pendulum is transmitted to the hands by a driving arm, fixed to the pendulum, which rocks a fork-shaped member pivoted at a fixed point and having a 45 driving pawl pivoted thereon and acting upon a ratchet which actuates the minute-hands through a suitable transmission. Furthermore, the said fork-shaped member, through contact of one of its prongs with 50 the driving arm establishes the electric connection which causes excitation of the coil actuating the pendulum, this excitation taking place in the neighborhood of the passage of the pendulum past the head centre 55 in one direction only, electric contact in the other direction being prevented by an in-

sulating packing carried by the driving arm or by the fork.

In order to facilitate understanding of the invention a form of execution of the mechanism fitted to a clock comprising a pendulum carrying a coil at its extremity, is described below. This coil moves in the neighborhood of a permanent magnet and periodically receives an impulse owing to 65 an electric current which passes through it at suitable intervals. But it is to be clearly understood that this form of execution is only given by way of example and that any other electric-magnetic system could be used 70 comprising the application of the action of a current upon a magnet (or upon another current or again upon a soft-iron armature) the only condition to be observed being that the effect of the passage of the current shall 75 be to give rise to a force of suitable value which acts upon the pendulum in a direction favourable to the upkeep of its oscillatory motion.

The clock in accordance with the invention is illustrated in the accompanying drawing, in which:

Figure 1 is a general front view with portions in section along line 1—1 of Figure 2.

Figure 2 is a side view with portions in section along line 2—2 of Figure 1.

Figures 3, 4, 5 and 6 are detail views showing the method of operation of the principal parts of the clock.

Figure 6^a is a front general view of a modification showing portions in section along line 1—1 of Figure 7.

Figure 7 is a side view with portions in section along line 2—2 of Figure 6^a.

Figure 8 is a plan view of this modified form.

Figure 9 is a detailed view of the fork shaped member according to this modification.

Figure 10 is a view of this member shown in section along line 5—5 of Figure 9.

Figure 11 is also a sectional view along line 6—6 of Figure 9.

Referring first to Figures 1 to 6, the clock 105 comprises a pendulum attached to the support 1 by a suitable suspension device S. The bob of the pendulum is shown at 2 fixed to the extremity of the rod 3. This rod 3 is in turn fixed to the crossbar T of the suspension device S of the pendulum.

A coil of fine insulated wire 4 is fixed to

the end of the pendulum. A permanent magnet 5, of which only a portion is shown in the figure, is arranged in such a manner that one of its extremities penetrates into 5 the coil and gives rise to an electromagnetic force acting in the direction of the arrow f_1 when the coil is traversed by an electric current.

The actuation of the hands is effected by 10 the pawl 6 acting upon the ratchet wheel 7 which is fixed to the worm 8.

This worm meshes with the toothed wheel 9 keyed on the shaft 10 of the minute hand 11.

15 The hour hand is actuated by an ordinary minute wheel-work.

The pawl 6 is pivoted at 13 on the fork-shaped member 14 which pivots about a fixed point 15 while the arm 16, fixed to the 20 pendulum acts upon the prongs thereof. The centre of gravity of this member 14 is located above this axis 15 so that, under the action of its weight, this member tends to fall back to left or right, but its angular 25 movement is limited by the stop 17 arranged in the notch e (Figure 5).

The arm 16 is made of a good conductor of electricity and is fixed on the cross-bar T of the suspension device and insulated 30 therefrom by plates and sleeves of insulating material.

One of the extremities of the coil 4 is connected to the frame-work, while the other extremity is connected to the arm 16 35 by the insulated conductor c .

On the other hand, at the end of the arm 16 there is fixed a small plate 18 of insulating material arranged as shown in the drawing.

40 The frame of the clock-work mechanism consists simply of the standard 19 in which is mounted the shaft of the ratchet wheel. This standard carries the arm 20 upon which is pivoted the rocking forked member 14 and 45 the arms 21 and 22 in which the axis 10 of the big hand rotates.

A source of electricity which may be constituted by an ordinary electric battery P is connected on the one hand to the support 50 1 which latter is electrically connected, as has been seen, to one of the extremities of the coil 4, and on the other hand to the standard 19 constantly in electric connection with the rocking fork 14 which is made of 55 material which is a good conductor of electricity.

The method of operation of the clock is as follows:

Starting from the position shown in Figure 3, the pendulum begins to oscillate in the direction of the arrow f_1 while the fork 14 is thrown over in the direction f_2 . A little before passing to the vertical position the conducting end of the arm 16 comes into 65 contact with the prong B' of the fork 14

and turns it in the direction f'_1 . Under these conditions, the pawl 6, being in engagement with one of the teeth of the ratchet 7, causes it to rotate as shown in Figure 4.

When the pendulum, continuing its stroke 70 in the direction f_1 , has passed the vertical, the fork falls back in the direction f'_1 and assumes the position shown in Figure 5.

The proportions of the parts are chosen such that the rotation of the ratchet 7 produced by the movement of the fork 14 corresponds to an advance slightly greater than one tooth. On the other hand, the position of the stop 17 is such that the prong B_1 of the fork 14 moves down and offers no resistance to the movement of the pendulum which continues its oscillation freely in the direction f_1 .

On the return of the pendulum in the direction f_2 , the insulating plate 18 carried by 85 the arm 16 acts upon the prong B_2 of the fork 14, as shown in Figure 6, and obliges the fork to turn in the direction f'_2 . Under these circumstances, the pawl 6 returns to the rear, but the ratchet wheel remains in 90 place, the nose of the pawl sliding over the back of the tooth, the friction of said nose not being sufficient to turn the ratchet-wheel backwards.

At the end of the stroke in the direction f_2 , 95 the pendulum and the fork 14 resume the position shown in Figure 3 and the operation just described is repeated in the same manner.

It will therefore be seen that, at each oscillation of the pendulum in the direction f_1 , the ratchet wheel moves forward by one tooth and an electric contact is produced between the conducting end of the arm 16 connected to one of the extremities of the coil 100 and, the fork 14, which is also a conductor, and is connected to one of the poles of the source of electricity. It will be seen that this electric contact closes the circuit comprising the battery P and coil 4. Under 105 these circumstances, a force is developed in the direction of the trajectory of the extremity of the pendulum, the direction and amount of said force can be easily determined so as to keep up the movement of the 110 pendulum.

It should be noted that the contact, and consequently the driving impulse, take place in the neighbourhood of the dead centre, a condition which, as is well known, is very 115 advantageous for the control of the clock.

Breakage of the circuit is very abrupt and the conducting surfaces which come into contact are kept perfectly clean and are consequently kept in good condition indefinitely. The mechanical operation of the system is also very sure and as can be seen, the mechanism only comprises parts which are very simple and of strong construction which can be assembled cheaply and easily.

It is evident that various modifications in detail could be made in the mechanism described above without departing from the scope of the invention.

5 According to a modification a brake is placed upon the shaft of the fork-shaped rocking member, this brake consisting of a spring which causes slight friction tending to resist the movement of this member when 10 the driving arm acts upon it. The shape of the said member is also modified in such a manner that it is balanced and consequently does not fall over under the action of its own weight. Instead of a driving arm 15 distinct from the rod of the pendulum there is provided a pin carried by the rod of the pendulum and engaging when the pendulum is near the vertical position, between the prongs of the fork-shaped member.

20 The space comprise between the two prongs of the fork one of which carries an insulating piece, is very slightly wider than the diameter of the pin. In this manner the result is obtained that the periodical 25 closures of the electric circuit, necessary to keep up the oscillating movement of the pendulum, are produced even if the amplitude of the oscillation is very small. If under these circumstances the pendulum is 30 almost completely stopped in consequence of a shock or movement of the clock, it progressively resumes its normal running owing to the successive attractions to which it is subjected.

35 The present invention also relates to an advantageous form of realization of the mechanism of the clock, the characteristic features of which will be evident from the following description.

40 In Figures 7 and 12 of the accompanying drawing the fork shaped piece is shown at 1^a. This piece is fixed to the shaft 2^a pivoted on a fixed frame B^a.

45 The fork 1^a is shown in detail in Figures 10, 11 and 12. Its form is such that its centre of gravity is in the neighbourhood of its axis so that it remains in equilibrium in any position. Upon the shaft 2^a bears a brake constituted by a leaf spring 3^a, one 50 of the ends of which acts upon the shaft with the interposition of a shoe 4^a preferably consisting of an alloy of bronze or graphite. The force and tension of the spring 3^a are 55 adjusted so that a slight friction is produced when the fork 1^a is moved.

The fork 1^a carries on the other side an insulating strip 5^a and a strip 6^a, preferably consisting of a metal which does not oxidize easily; such as silver (Figures 10 and 11).

60 The strips form the boundaries of a notch e^a in which the pin 7^a fixed to the pendulum P^a can engage, the rod of the pendulum being shown at 8^a, Figures 7, 8 and 9. The width of the notch e^a is very slightly greater 65 than the diameter of the pin 7^a. This pin

70 consists of a metal which is a good conductor of electricity and does not oxidize easily, such as silver. It is fixed on the rod 8^a while at the same time being insulated electrically therefrom.

This result can be obtained by fixing the pin on a two part collar 9^a and 10^a tightly clamped by means of screws 11^a and 12^a to the rod 8^a an insulating sleeve 13^a being 75 interposed.

The pin 7^a and the fork 1^a are interposed in the electric circuit feeding the clock. For example, in the case of a clock whose pendulum carries at its extremity a coil moving in the neighbourhood of a fixed magnet, 80 the electric circuit can be formed in the following manner. One of the poles of the source of current is connected to the rod 8^a of the pendulum by the intermediary of the suspension device and one of the extremities of the movable coil is connected to the framework in such a manner as to be 85 connected electrically to the pole in question.

The other extremity of the coil is connected by an insulated conductor 14^a to the 90 conducting pin 7^a. Finally the other pole of the source is connected to the frame of the mechanism B^a which should be insulated from the support S^a of the pendulum. This pole is thereby connected to the fork-shaped 95 piece 1^a by means of the pivots and also of the brake 4^a, in the case of which latter every precaution is taken in order to ensure a good electric contact.

The general principle of operation is the 100 same as that described in detail in the prior form of construction. At each stroke in the direction f^a, and in the neighbourhood of the passage of the pendulum through the vertical line, the electric circuit is closed and 105 consequently a driving impulse is given. But it should be remarked that when the fork shaped piece 1^a is moved, the friction produced by the spring 3^a is opposed to its movement and that this latter does not fall 110 under the action of its own weight.

The result is that the operation of the device is modified in the following manner:

When the pendulum, starting from the 115 position shown in Figure 7, moves in the direction f^a contact is established as soon as the pin 7^a acts upon the conducting edge of the notch e^a and the fork 1^a, see Figure 10. This latter is moved in the direction f^a and contact is continued until the pin 120 leaves the notch. In view of its inertia the fork 1^a continues this movement by a slight amount and the electric current is broken. For this to happen it is necessary that the 125 form of the upper parts of the prongs of the fork should be such that they do not touch the pin 7^a while the pendulum continues its stroke. The friction of the spring 3^a is sufficient to maintain the fork 1^a in position as soon as the pin ceases to act 130

upon it. By this means the shocks of this fork upon the abutments, and the disagreeable noise caused thereby, are avoided. Moreover, the friction permits of slightly increasing the pressure of the pin on the contact portion and thereby to improve the electric contact.

The device which has just been described gives the extremely advantageous result that the pendulum resumes its normal running automatically even if its oscillation is almost completely stopped. It will be seen that the width of the notch 8^a , being very little greater than the diameter of the pin, the periodic closures of the electric current necessary to keep up the movement of the pendulum are ensured even if the amplitude of this movement is very small. The velocity being then very reduced, the counter electro-motive force is almost zero and the intensity attains a high value which gives rise to relatively strong attractive effort by means of which the amplitude increases little by little until the value corresponding to normal running is attained.

It should be remarked that this feature has not been obtained in systems realized up to the present, for below a certain amplitude the periodic closures and the electric current cease to be ensured. This feature is very important especially in the case of clocks in offices or on mantel-pieces which may be liable to receive accidental shocks which would cause considerable reduction in the amplitude of oscillation of the pendulum. With the system forming the subject of the present invention the clock resumes its motion even if the pendulum has been stopped almost entirely.

Another characteristic feature of the invention relates to an improved form of construction of the frame B^a of the mechanism. This frame is very simple constituted by a stay 15^a upon which is fixed a member 16^a , constituted by a piece of tube of square section in which notches have been milled for the passage of the various inovable parts as shown in the drawing.

The shaft 2^a of the fork 1^a is pivoted on the stay 15^a for fixing the mechanism and on the bridge piece 17^a fixed, by means of the screw 18^a , on the front face of the square tube 16^a . A ring 19^a fixed to the end of the shaft 2^a resists longitudinal movement of this shaft.

The ratchet 20^a is fixed to the extremity of the shaft 21^a upon which is fixed the worm 22^a meshing with the toothed wheel 23^a , which latter is pinned upon the shaft of the minute hand 24^a . This shaft pivots in two holes formed on the vertical faces of the square tube 16^a . The vertical shaft 21^a of the ratchet also pivots in two holes pierced in the horizontal faces of the tube 16^a . Pawl 25^a is pivoted on the fork 1^a as

shown in Figure 12. As will be seen, this method of construction only requires parts which can be easily machined and can be assembled conveniently and economically. It will be noticed that the holes in which 70 pivot the two shafts of the worm and of the toothed wheel meshing therewith, being pierced in one and the same part which is perfectly rigid, it is more easy to obtain at first hand in the case of mass-production an 75 exact and inalterable distance apart of the axes than when using supports consisting of a plurality of pieces connected together, as is generally the case in clockwork mechanism.

I claim:

1. In an electric clock, the combination with a pendulum, an electric coil fixed to said pendulum and a fixed permanent magnet, co-operating with said coil, of an arm 85 rigidly fixed to said pendulum a forked rocking member adapted in operation to be alternately engaged by and disengaged from the said arm, and means carried by said rocking member for actuating the clock- 90 work mechanism.

2. In an electric clock, the combination with a pendulum, an electric coil fixed to said pendulum and a fixed permanent magnet co-operating with said coil, of an arm 95 rigidly fixed to said pendulum, a forked rocking member adapted in operation to be alternately engaged by and disengaged from the said arm, means carried by said rocking member for actuating the clockwork 100 mechanism and means for arresting the motion of said rocking member after its release by the arms.

3. In an electric clock, the combination with a pendulum, an electric coil fixed to 105 said pendulum and a fixed permanent magnet co-operating with said coil, of an arm rigidly fixed to said pendulum, a forked rocking member adapted in operation to be alternately engaged by and disengaged from 110 the said arm, an electric circuit comprising a source of current and said electric coil, a gap in said circuit, between said arm and said rocking member, adapted to be opened and closed thereby, and means for preventing 115 electric contact between said arm and said rocking member, in one direction of oscillation only.

4. In an electric clock, the combination with a pendulum, an electric coil fixed to 120 said pendulum and a fixed permanent magnet co-operating with said coil, of an arm rigidly fixed to said pendulum, a forked rocking member adapted in operation to be alternately engaged by and disengaged from 125 the said arm, means carried by said rocking member for actuating the clockwork mechanism, an electric circuit comprising a source of current and said electric coil, a gap in said circuit, between said arm and said rock- 130

- ing member, adapted to be opened and closed thereby, and means for preventing electric contact between said arm and said rocking member, in one direction of oscillation only.
5. In an electric clock, the combination with a pendulum, an electric coil fixed to said pendulum and a fixed permanent magnet co-operating with said coil, of an arm rigidly fixed to said pendulum, a forked rocking member adapted in operation to be alternately engaged by and disengaged from the said arm, an electric circuit comprising a source of current and said electric coil, a gap in said circuit, between said arm and said rocking member, adapted to be opened and closed thereby, and an insulating piece interposed between said arm and one of the prongs of said forked rocking member.
6. In an electric clock, the combination with a pendulum, an electric coil fixed to said pendulum and a fixed permanent magnet co-operating with said coil, of an arm rigidly fixed to said pendulum, a forked rocking member adapted in operation to be alternately engaged by and disengaged from the said arm, means carried by said rocking member for actuating the clock-work mechanism, an electric circuit comprising a source of current and said electric coil, a gap in said circuit, between said arm and said rocking member, adapted to be opened and closed thereby, and an insulating piece interposed between said arm and one of the prongs of said forked rocking member.
7. In an electric clock, the combination with a pendulum, an electric coil fixed to said pendulum and a fixed permanent magnet co-operating with said coil, of an arm rigidly fixed to said pendulum, a forked rocking member adapted in operation to be alternately engaged by and disengaged from the said arm, a pawl carried by said rocking member, a ratchet wheel connected to the shaft of the clock-work mechanism, said pawl co-operating with said ratchet wheel, an electric circuit comprising a source of current and said electric coil, a gap in said circuit, between said arm and said rocking member adapted to be opened and closed thereby, and means for preventing electric contact between said arm and said rocking member during the return stroke of said pawl.
8. In an electric clock, the combination with a pendulum, an electric coil fixed to said pendulum and a fixed permanent magnet co-operating with said coil, of an arm rigidly fixed to said pendulum, a forked rocking member adapted in operation to be alternately engaged by and disengaged from the said arm, means carried by said rocking member for actuating the clock-work mechanism, and a brake permanently acting upon said rocking member for arresting its motion after its release by the arm.
9. In an electric clock, the combination with a pendulum, an electric coil fixed to said pendulum and a fixed permanent magnet co-operating with said coil, of an arm rigidly fixed to said pendulum, a forked rocking member adapted, in operation, to be alternately engaged by and disengaged from the said arm, an electric circuit comprising a source of current and said electric coil, a gap in said circuit, between said arm and said rocking member, adapted to be opened and closed thereby, means for preventing electric contact between said arm and said rocking member, in one direction of oscillation only, and a brake permanently acting upon said rocking member for arresting its motion after its release by the arm.
10. In an electric clock, the combination with a pendulum, an electric coil fixed to said pendulum and a fixed permanent magnet co-operating with said coil, of an arm rigidly fixed to said pendulum, a forked rocking member adapted, in operation, to be alternately engaged by and disengaged from the said arm, means carried by said rocking member for actuating the clock-work mechanism, an electric circuit comprising a source of current and said electric coil, a gap in said circuit, between said arm and said rocking member, adapted to be opened and closed thereby, means for preventing electric contact between said arm and said rocking member, in one direction of oscillation only, and a brake permanently acting upon said rocking member for arresting its motion after its release by the arm.
11. In an electric clock, the combination with a pendulum, an electric coil fixed to said pendulum and a fixed permanent magnet co-operating with said coil, of an arm rigidly fixed to said pendulum, a forked rocking member adapted, in operation, to be alternately engaged by and disengaged from the said arm, means carried by said rocking member for actuating the clock-work mechanism, an electric circuit comprising a source of current and said electric coil, and a gap in said circuit, between said arm and said rocking member, adapted to be opened and closed thereby, means for preventing electric contact between said arm and said rocking member, in one direction of oscillation only, and a brake permanently acting upon said rocking member for arresting its motion after its release by the arm.

MAURICE PHILIPPE FAVRE-BULLE.
